UNITED STATES PATENT OFFICE.

JOHN H. MATTICE, OF CLYDE, KANSAS.

CALENDAR.

Application filed March 26, 1923. Serial No. 627,771.

To all whom it may concern:

Be it known that I, JOHN H. MATTICE, a citizen of the United States, residing at Clyde, in the county of Cloud and State of Kansas, have invented certain new and useful Improvements in Calendars; and I do declare the following to be a full, clear, and exact description of the invention, such as will enable others skilled in the art to which it appertains to make and use the same.

My invention relates to improvements in calendars of the type having relatively shiftable exhibitors capable of being set in a manner to provide a calendar which can be used for a great number of years.

The principal object of the invention is to provide a calendar which will be extremely simple and inexpensive, yet will be absolutely accurate, the construction and arrangement of characters being such that it is not necessary to keep in mind a great number of rules governing thirty day months, thirty-one day months, the twenty-eight day month of February, and the leap years in which February has twenty-nine days.

With the foregoing in view, the invention resides in the novel subject matter herein-after described and claimed; the description being supplemented by the accompanying drawings.

Figure 1 is a front elevation of a calendar constructed in accordance with my invention.

Figures 2 and 3 are front elevations of the two movable exhibiting disks.

Figure 4 is an elevation of the face plate.

Figure 5 is a vertical sectional view showing the relation of the face plate and the two exhibiting disks, and the operating means for the latter.

In the form of construction selected for illustration in the present application, the numeral 1 designates a suitably shaped face plate having two elongated slots 2 and a relatively large opening 3. The calendar disclosed is for the nineteenth and twentieth centuries and I print the face plate 1 with the numbers 18 and 19, adjacent said slots 2. The number 18 co-operates with certain additional numbers to be displayed in one of the slots 2, to represent the years 1800 to 1899, while the numeral 19 co-operates with additional numbers displayed in the other slot 2, to represent the years 1900 to 1999. For want of a better expression, I

have hereinafter referred to the numbers 18 and 19 as century numbers, as they each represent several hundred years.

One edge of the opening 3 is printed with letters or other week day designations 4, these designations being co-operative with a plurality of month day numbers 5 on a movable exhibiting disk 6 disposed behind the face plate 1 and in the present instance pivoted to the latter at a central point. The numbers 5 are disposed in thirteen radial columns and any seven of these columns may be viewed at one time in the opening 3, in alinement with the week day designations 4. The central column of the numbers 5 contains the numbers 1, 8, 15, 22 and 29, reading downwardly; the numbers at the right of these specified numbers, increase consecutively from said specified numbers; and the numbers at the left of said specified numbers increase successively toward the same. The numbers 30 are distinctively printed as indicated at 5^a and in order that certain descriptive matter to follow hereinafter may be more fully understood, attention may be directed to the fact that the number 30 is the last day of any of the four months, April, June, September and November. The number 29 on the disk is also distinguished from the others, for instance by underscoring the same as indicated at 5^b, representing the last day of February in leap years.

In the present showing, the disk 6 is provided with a suitable stop 7 to engage the end walls of the opening 3 to limit the movement of said disk with respect to the face plate 1, and in order that this disk will not at times cover the slots 2 of said face plate, its upper portion is preferably formed with an arcuate opening 8. I also form a relatively small opening 9 in the disk 6, through which the names of the months may be viewed, this opening being preferably positioned in such a manner that it is at all times within the area of the opening 3.

A second exhibiting disk 10 is disposed behind the disk 6 and is pivoted co-axially therewith. The peripheral portion of this disk is printed with legends representing the twelve months of the year and the four thirty day months, April, June, September and November, are distinctively printed to correspond with the distinctive printing of the numbers 30 of the group 5. Thus, when any of these distinctively printed month legends appears through the opening 9, at

tention is directed by the distinctive printing thereof, compared to the similar printing of the numbers 30, that this particular month has thirty days. The legends representing the four thirty day months are indicated on the drawings by the reference numeral 11, the legend for February is indicated at 12 and is preferably underlined as at 13, and the other month legends are 10 designated by the numerals 14.

In addition to the data above described, the disk 10 is printed with a plurality of radial columns 15 of year numbers which co-act with the century numbers 18 and 19 on the 15 face plate 1 to represent different years. For instance, in the right hand slot 2 of Fig. 1, the years 1901, 1907, 1912, 1918, etc., are represented. There are a number of these 20 columns, and their arrangement allows seven columns for each month corresponding to the seven calendars for the month appearing in the opening 9, and the numbers of the individual columns are arranged in a manner which can be more clearly illustrated than described, reference being therefore directed to Fig. 3 in particular. It will be observed that certain of the numbers are underscored as indicated at 16. These 25 underscored numbers represent the leap years, in which February has twenty-nine days, and when the calendar is set for instance to show the days of February 1924, the numeral 24 appearing in the column exposed at the right hand slot 2, will be underscored, the 30 month legend 12 for February, appearing in the opening 9 will be similarly underscored, and the month day number 29 of the disk 6 will also be underscored. It is thus clear 35 that the underscored 29 is the last day of February in the particular leap year in question.

By properly setting the calendar, the month days of any month and any year, within limits, may be displayed in the opening 45 3. For instance, when the back exhibiting disk 10 is set so that the desired month legend is displayed through the opening 9 and the two exhibiting disks 6 and 10 are bodily turned until the required year number 50 15 is exposed through one of the slots 2 for co-action with the proper century designation 18 or 19, then the columns of numbers 5 on the disk 6 are properly aligned with the week day designations 4. When set as 55 shown in Fig. 1, the device will show the month days for September and December 1805, 1811, 1816, etc., and 1901, 1907, 1912, 1918, etc. In all instances, by turning the exhibiting disk 10 to show the proper month 60 legend through the opening 9 and after this has been done, simultaneously turning the two disks 6 and 10, until the desired year number appears in the proper column 2, the numbers 5 on the exhibiting disk 6 are automatically set in proper relation with the

week day designations 4. If the particular month legend displayed through the opening 9 is a thirty day month, comparison of its distinctive printing with the distinctively printed number represented by the reference 70 numeral 5^a, will show this at a glance. If the year at which the calendar is set is a leap year, the underlining 16 appearing in the slots 2, will show this and the underlining 5^b under the number 29 in the opening 75 3 shows that whenever the month February appears in the opening 9, this month will have twenty-nine days in all the underlined years now appearing in the slots.

The columns 15 may be said to possess representative numbers at their outer or upper ends, when presented in the slots 2, and the number of years which may be found under these representative numbers, may be given in printed directions on the back of the calendar if desired. Also, similar notations with respect to the underlining and the distinctive printing of certain numbers may be given.

In the preferred form of construction, selected for illustration in the present application, the three members 1, 6 and 10 are frictionally engaged with each other, an operating knob 20 is provided for the exhibiting disk 6, and an operating rib or the like 80 21 around said knob is employed for the back exhibiting disk 10. I wish it understood however that the exact association of parts shown is not essential as in some instances, the exhibitors need not be circular, 85 and need not be pivotally mounted, but could well slide instead of having rotary or pivotal movement.

A calendar constructed in accordance with the present disclosure has proven to 90 be absolutely accurate for the entire nineteenth and twentieth centuries, and it is not a difficult matter to adjust the device for any year desired, within this period. It will be understood that the period of 95 time represented by the calendar is determined by the century numbers and the columns of year numbers shown on plate 10. Therefore, the location of the slots, the opening 3, the opening 9, and the arrangement 100 of the numerous characters on the calendar are unchangeable in their relation to each other, though they may be varied otherwise in numerous ways, within the scope of the invention as claimed.

I claim:

A calendar comprising a face plate having two slots and century members adjacent said slots, said face plate also having an opening and week day designations along one edge thereof; a movable exhibitor behind said face plate having thirteen columns of month day numbers any seven columns of which may be viewed simultaneously through said opening in line with said week 120 130

day designations, the central column of said month day numbers containing the numbers 1, 8, 15, 22, and 29 reading from top to bottom, the numbers of the columns at the right of said central column increasing consecutively from the above specified numbers while the numbers of the columns at the left of said central column increase consecutively toward said specified numbers, the number 29 being distinctively displayed to show the last day of February in leap years while the numbers 30 are also distinguished from the others to show the last day of April, June, September and November; and a second movable exhibitor behind said first named exhibitor having twelve month legends with the legends of April, June, Sep-

tember and November distinctively displayed to correspond with the manner of distinguishing the numbers 30 from the other month day numbers, said first named exhibitor having an opening through which any of said legends may be seen when the two exhibitors are properly set with respect to each other, said second exhibitor having columns of year numbers for presentation at the slots of said face plate to co-operate with said century numbers to show numerous years, the leap year numbers being distinctively displayed to correspond with the manner of distinguishing the month day 29.

In testimony whereof I have hereunto affixed my signature.

JOHN H. MATTICE.
